TOY GUN

Filed March 11, 1930

UNITED STATES PATENT OFFICE

FADER KESELEFF, OF SEATTLE, WASHINGTON

TOY GUN

Application filed March 11, 1930. Serial No. 434,899.

My invention relates to an improvement in toy guns, and particularly to the type where a projectile is shot forward outside the casing or barrel of the gun.

5 The object of my invention is to provide a toy gun having the general shape of a gun, and having a projector adapted to carry the projectile outside of the barrel and to propel it forward in the line of the sight.

10 Another object is to provide a casing representing the outline of a barrel of a gun and having novel securing means relative to the gun proper.

15 A further object is the construction of a device of this general character, which shall be simple and strong and will stand the rough usage generally required by children.

20 My invention comprises the novel parts and the novel combination and arrangement thereof, as shown in the accompanying drawings, described in the specification and particularly defined by the claims terminating the same.

25 In the accompanying drawings I have shown my invention in the form now preferred by me.

Figure 1 is a side elevation of my gun showing the projector in cocked position and with a ball in place.

30 Figure 2 is a central longitudinal section of my gun.

Figure 3 is a section on the line 3—3 of Figure 2, showing a portion of the ball in dotted lines.

35 Figure 4 is a plan view of the tip of the gun showing the slide and projector in a forward position and showing parts of the tip in section and with the casing removed.

40 Figure 5 is a fragmentary plan view illustrating my method of attaching the casing to the breech.

45 My gun in general conforms to the shape of any standard rifle, and comprises a stock 1, which may be made of wood, and a breech 10, which is usually made of metal. The stock and breech may be secured together in any suitable manner.

50 In order to form a foundation for the barrel of the gun, I may provide two parallel spaced bars 2 which may be seated in sockets

11 of the breech 10 and held securely by set screws 12. The forward end of these bars 2 are tied together by a tip member 3 having sockets 30 adapted to receive the forward end of the bars 2. The bars may be held secure in the member 3 by set screws 31.

The bars 2 also have another use in that they act as guide bars for the slide 4. The slide consists in a front cross bar 40 and a rear cross bar 41 spaced apart and they may be tied together by a rod 42. Such a construction produces a slide which will slide easily upon the guide bars and eliminate binding and a tendency to wobble. In order to impart a forward movement to the slide 4, a resilient rubber band 5 may be attached to a removable bolt 32 secured in and interposed between two downwardly projecting lugs 33 at the tip of the gun. At the rear the band 5 may be attached to a similar bolt 43 secured in, and interposed between two downwardly extending lugs 44 depending from the rear cross bar 41.

An upstanding longitudinal vane 45, rigidly secured to the cross bars 40 and 41, is provided with a forwardly projecting finger 46, upon which the projectile may be positioned, as will be explained hereinafter. In order to pull the carriage back, a suitable finger piece 47 is secured on the rear portion of the vane 45.

It is, of course, desirable to hold the slide when it is brought back to the farthest rear position. A trigger guard 5 is secured on the under side of the breech 10 by screws 51, a trigger 50 is pivotally mounted in the guard 5. A spring-held plunger 52 normally tends to raise the plunger upward against a plate 13 which is held in place by a screw 14. The plate is further held by a tongue 15 which fills the rear portion of a longitudinal groove 16 in the breech block. A rearwardly projecting apertured lip 41', integral with or forming a part of the rear cross bar 41 of the slide, is adapted to project into the forward portion of the groove 16; the spring plunger enters the aperture and thereby holds the slide in cocked position. To release the slide, the trigger 5 is pulled, thereby pulling down 100

the plunger 52 and allowing the lip free forward passage.

The forward shock of the slide is taken up by a bumper bar 6, slidably mounted on 5 guide bars 2, and provided with a plunger 61 received in a bore 34 of the tip member 3 and bearing against the spring 35 mounted thereon.

In order to produce the effect of a gun barrel and at the same time enclose the rods 2, 10 slide 4 and resilient band 5, against dirt and damage, and also guarding the fingers of the operator against being hurt, a casing 7 is provided. The upper surface has a longitudinal 15 slot 73, of sufficient length to allow free movement of the upstanding vane 45. The lower rear edge of the casing at 71 is received in a slot 17 in the breech. The upper rear portion of the casing may be formed as a split 20 tongue 72 and inserted under a staple 18 secured in the plate 13. The staple prevents side movement of the casing. To hold the casing securely in place, a screw 36 may be received in the tip member 3.

25 The ammunition for my gun consists of a soft rubber ball 8, which is provided with a hole part way through its axis, in which is positioned a bushing 80. The rubber ball 8 is placed upon the finger 46 with the bushing 30 80 loosely fitting about the finger. The upstanding vane 45 is so shaped as to receive the ball against the edge 48 and frictionally hold it, due to the rubber ball being compressed, until the shock of the slide against 35 the bumper 6 is greater than the frictional holding of the ball, when it is released. The ball 8, vane 45 and finger piece 48 are all positioned and adapted to travel in a longitudinal plane outside of the casing 7, but this is all of 40 the mechanism which is exposed, and it is at the top of the casing or barrel 7, where it is not likely to harm the child who plays with the gun.

To replace a broken or worn-out rubber band 5, it is only necessary to remove the screw 36, whereupon the barrel 7 may be removed, and the bolts 32 and 43 may then be reached and quickly removed and replaced.

What I claim as my invention is:

45 1. In combination, in a toy gun, a breech member, a guide member extending forwardly from said breech member, a slide mounted on said guide member, means to project said slide forwardly, means to check the advance thereof, a casing surrounding and inclosing said guide member, slide and projecting means and having a narrow slot in its upper side for a portion of its length corresponding to the travel of the slide, an upstanding projectile carrier fixedly supported upon said slide and projecting through said slot, to support a ball unrestrained by the casing, and to propel the same forwardly as the slide is projected forward and is checked.

50 2. In combination, a toy gun, a breech

member, a casing adapted to represent the barrel of a gun and having a narrow slot in its upper side for a portion of its length, means interengageable between the breech end of the casing and said breech member by longitudinal movement of the casing to hold the casing to the breech, guide means, a screw positioned at the forward end of said guide means and engaging said casing to hold it in position, a slide upon said guide means, and means for projecting said slide forwardly and for checking its advance, all within the casing, and a projectile carrier extending through the slot in the casing and adapted to support and propel a ball forwardly outside the casing.

55 3. In combination, in a toy gun, a breech, a casing adapted to represent the barrel of a gun and removably secured to said breech, and having a slotted upper surface extending substantially from the breech to the tip of the barrel, said breech having a notch adapted to receive the rear lower end of said casing, a staple secured transversely in the top of said breech, a rearwardly extending tongue projecting from the upper portion of said casing and projecting through said staple to be held thereby, and means for holding said casing in a fixed position.

60 4. In combination with a toy gun, a casing having a narrow elongated slot in its upper surface, a slide adapted to be projected within the casing, a projectile carrier comprising an upstanding vane secured to and movable with said slide and projecting through said slot, said vane having a forwardly projecting finger, a projectile having a bore therein and adapted to be received upon said finger.

65 5. The combination of claim 4, the projectile being of resilient material, and frictionally engaging the projectile carrier to prevent accidental disengagement therefrom.

70 6. In combination with a toy gun, a breech member, a guide member extending forwardly from said breech member, and terminating at the other end in a tip member, said tip member having a socket parallel to the guide member, a spring in said socket, a bumper member slidably supported on said guide member, a forwardly projecting plunger mounted on said bumper member and adapted to be received in said spring socket, a slide mounted upon said guide member, a resilient member secured by one end to said tip member and by the other to said slide to project said carrier against said bumper, and a projectile carrier associated with said slide.

75 7. In combination with a toy gun, a breech member, two horizontally spaced guide members secured by one end to said breech member and rigidly secured together at the other end by a tip member, a slide mounted on said guide members, a projectile supporting means projecting upwardly from said slide, resilient means connecting said slide with

said tip member to urge the slide forward, a trigger holding means mounted in said breech member and adapted to hold or release said slide, a casing enclosing said guide members, 5 tip member, slide and resilient means, and having a portion of its top slotted to allow movement of the upwardly projecting projectile supporting means and means for securing said casing to the breech.

10 Signed at Seattle, King County, Washington, this 5th day of March, 1930.

FADER KESELEFF.
